C. WEINBERG.

GIMP.

No. 18,619.

Patented Sept. 18, 1888.

UNITED STATES PATENT OFFICE.

CHARLES WEINBERG, OF NEW YORK, N. Y., ASSIGNOR TO C. WEINBERG & CO., OF SAME PLACE.

DESIGN FOR GIMP.

SPECIFICATION forming part of Design No. 18,619, dated September 18, 1888.

Application filed July 25, 1888. Serial No. 281,020. Term of patent 7 years.

To all whom it may concern.

Be it known that I, CHARLES WEINBERG, of the city, county, and State of New York, have invented a Design for Gimp, of which the following is a specification.

The accompanying photograph shows my design; and it consists in the design of the pattern of the gimp.

The design of the pattern consists in the cord ornaments 1 in the middle of the gimp, with transverse bars 2, and with small loops 3 at the edges of the gimp, and longitudinal bands 4 between the loops 3 and the cord ornaments 1, and bars 5 crossing the longitudinal bands 4.

I claim—

The design for gimp, consisting in the pattern of the cord ornaments 1 in the middle of the gimp, with transverse bars 2, and the longitudinal bands between the cord ornaments and the edges of the gimp, with the bars 5 crossing the longitudinal bands, substantially as shown. 20

Signed by me this 19th day of July, 1888.

CHARLES WEINBERG.
